SOCK

Oscar Frégeolle, Central Falls, R. I., assignor to Rhody Knit, Inc., a corporation of Rhode Island

Application May 18, 1953, Serial No. 25,081

Term of patent 7 years

(Cl. D47—7)

To all whom it may concern:

Be it known that I, Oscar Frégeolle, a citizen of the United States of America, residing in Central Falls, county of Providence, State of Rhode Island, have invented a new, original, and ornamental Design for a Sock, of which the following is a specification, reference being had to the accompanying drawing, forming a part thereof.

The figure is an elevation of a sock showing my new design. The opposite side is a duplicate of this design.

I claim:

The ornamental design for a sock, substantially as shown and described.

OSCAR FRÉGEOLLE.
